ARTICLE CARRIER

Charles J. Anchor, Buffalo, N. Y., assignor to
American Car and Foundry Company, New
York, N. Y., a corporation of New Jersey

Application February 19, 1944, Serial No. 523,166

6 Claims. (Cl. 294—67)

This invention relates to article carriers in general and in particular to carriers for hot shells during heat treat.

In order that shells will give the proper fragmentation upon explosion, it is necessary that they be properly heat treated. To obtain proper heat treat, it is, of course, necessary that the interior and exterior surface of the shell be fully and equally cooled at the same rate. Shells have generally been heat treated in the past by sliding them into the oil tanks on roller conveyors, then lifting them out by means of conveyer elevators, but with such an arrangement the shell surfaces are not equally cooled since parts are in contact with the rollers of the conveyer or slide and also in contact with each other. Also, oil or other cooling medium can not properly be placed inside the shell. It is an object, therefore, of the present invention to provide a carrier for hot shells, which carrier will engage the shells at a minimum number of points of small area.

A further object of the invention is the provision of a carrier which may be readily engaged with the shell for lifting the shell off of the hot shell conveyer and for transporting the shell to the quenching tanks.

A still further object of the invention is the provision of a shell carrier which may be readily engaged with the hot shells when in a horizontal position and which will bring the shells automatically to an upright nose down position for transport to the carrier tanks.

These and other objects of the invention will be apparent to persons skilled in the art from a study of the following description and accompanying drawings, in which

Fig. 1 is an elevational view of the carrier in full engagement with a shell on the conveyer;

Fig. 2 is a plan view of the carrier;

Fig. 3 is an end view of the carrier;

Fig. 4 is a view similar to Fig. 1 but showing the manner in which the carrier may be engaged with the shell, and

Fig. 5 is a view showing the shell lifter when the shell nose is resting on the floor.

Referring now to the drawing in detail, it will be seen that the carrier is made of two main parts, namely, a top member A and a bottom member B. The top member is formed with two straps 2, connected together at their top by a cross member 4, to which is connected a hoist receiving loop 6. The opposite or lower ends of the straps are provided with pivot pins 8, while

intermediate portions of the straps are tied together by cross ties 10 and 12, the latter being placed in such a position as to prevent accidental movement of the shell out of the carrier.

The lower member of the carrier is made up of bars 14 mounted at their upper end on pivot pins 8 and connected together adjacent their lower ends by a ring 16. The bars are also connected together adjacent the pivot pins by means of an open sided annulus 18. This is formed as substantially a three-quarter annulus and is formed with lugs 20. These lugs, as clearly shown in Fig. 3, are spaced approximately one hundred and twenty degrees apart and are relatively small so as to give a small area of contact with the body of the shell. The shell S is shown as supported on rollers R of the hot shell conveyer C, which conveyer supports the hot shells as they leave the heating furnaces.

As shown in Fig. 4, the carrier in engaging the shell may be pushed or slid from the full line position to the line and dash position. This may be easily done since the bottom member will rest on the floor F in such a position that the pivot 8 and bars 14 are substantially in the horizontal plane through the axis of the shell. The carrier may thus be readily kicked or pushed into engagement with the shell and without disturbing the shell as it rests either on the conveyer or upon the floor plate F in case it has overshot the end of the conveyer. With the carrier in the line and dash position the hoist will be operated, pulling up on straps 2 and bringing the shell to an upright position, since the pivot 8 will be between the center of gravity of the shell and the base. With the shell in the vertical position as shown in Fig. 5 it may be lowered into the tanks containing the cooling medium and the cooling medium may be freely circulated both onto the inside and outside surfaces of the shell and will contact substantially the entire surfaces. It will be seen that the only areas which the cooling medium can not freely contact are those areas partially blanked by small lugs 20 and the small area of contact of ring 16 with the nose of the shell. If for any reason the shell should be lowered onto the floor, as shown in Fig. 5, the carrier could not be disengaged from the shell or the shell tip out of the carrier, for the cross bar 12 would engage the base of the shell as shown and prevent pivoting movement between the top and bottom members.

While the construction has been described more or less in detail with specific reference to the

drawing, it will be obvious that various modifications and rearrangements of parts may be made and all such modifications and rearrangements of parts are contemplated as fall within the scope of the appended claims defining my invention.

What is claimed is:

1. In a shell lifter the combination of a top member adapted to be connected to a hoist, said top member including spaced straps and pivot pins carried by the straps adjacent their lower ends, a bottom member including spaced bars mounted adjacent their upper ends on said pivot pins, a ring connecting said bars together adjacent their lower ends and adapted to receive the nose portion of a shell, and a substantially three quarter annulus connecting said bars together adjacent said pivot pins and adapted to engage the shell body intermediate the nose and base portions.

2. In a shell lifter the combination of a top member adapted to be connected to a hoist, said top member including spaced straps and pivot pins carried by the straps adjacent their lower ends, a bottom member including spaced bars mounted adjacent their upper ends on said pivot pins, a ring connecting said bars together adjacent their lower ends and adapted to receive the nose portion of a shell, and a substantially three-quarter annulus connecting said bars together adjacent said pivot pins and adapted to engage the shell body intermediate the nose and base portions, said three quarter annulus being formed with lugs contacting the shell body at three substantially equally spaced points.

3. In a shell lifter the combination of a top member adapted to be connected to a hoist, said top member including spaced straps and pivot pins carried by the straps adjacent their lower ends, a bottom member including spaced bars mounted adjacent their upper ends on said pivot pins, a ring connecting said bars together adjacent their lower ends and adapted to receive the nose portion of a shell, an open sided annulus connecting said bars together adjacent said pivot pins, and lugs formed on the inner side of said open sided annulus and adapted to engage the body of the shell at spaced points.

4. In a shell lifter the combination of a top member adapted to be connected to a hoist, said

top member including spaced straps and pivot pins carried by the straps adjacent their lower ends, a bottom member including spaced bars mounted adjacent their upper ends on said pivot pins, a ring connecting said bars together adjacent their lower ends and adapted to receive the nose portion of shell, an open sided annulus connecting said bars together adjacent said pivot pins, and three lugs formed on the inner side of said open sided annulus, said lugs being spaced substantially 120 degrees apart whereby they may engage the body of the shell at spaced points and with small areas of contact.

5. In a lifter for immersing hot shells in a cooling medium the combination of, a top member adapted to be connected to a hoist, said top member including spaced straps and pivot pins carried by the straps adjacent their lower ends, a bottom member including spaced bars mounted adjacent their upper ends on said pivot pins, a ring connecting said bars together adjacent their lower ends and adapted to receive the nose portion of a shell, a substantially three quarter annulus connecting said bars together adjacent said pivot pins, and spaced lugs formed on said annulus and adapted to engage the body of the shell to lift the same, said lugs and ring contacting the shell in small areas of contact whereby the cooling medium may contact substantially the entire shell area.

6. In a shell lifter the combination of a top member adapted to be connected to a hoist, said top member including spaced straps and pivot pins carried by the straps adjacent their lower ends, a bottom member including spaced bars mounted adjacent their upper ends on said pivot pins, a ring connecting said bars together adjacent their lower ends and adapted to receive the nose portion of a shell, and a substantially three quarter annulus connecting said bars together adjacent said pivot pins adapted to engage the shell body intermediate the nose and base portions, and means connecting said spaced straps adjacent said pivot pins and so arranged as to be engageable with the shell base to prevent accidental movement of the carrier out of engagement with the shell.
